United States Patent

Des. 236,644
Patented Sept. 2, 1975

236,644

PENDANT

Benny L. Stowe, 1003 Sunset, Marshall, Tex. 75670

Continuation-in-part of abandoned design application Ser. No. 368,714, June 11, 1973. This application Dec. 23, 1974, Ser. No. 535,993

Term of patent 14 years

Int. Cl. D11—01

U.S. Cl. D45—15

FIG. 1

FIG. 2

FIG. 3

FIG. 4

FIG. 5

FIG. 1 is a front elevational view of a pendant showing my new design;

FIG. 2 is a cross section thereof taken on line 2—2 of FIG. 1;

FIG. 3 is a right side elevational view thereof;

FIG. 4 is a rear elevational view thereof; and

FIG. 5 is a top plan view thereof.

This is a continuation-in-part of design application Ser. No. 368,714, filed June 11, 1973, now abandoned.

I claim:

The ornamental design for a pendant, as shown.
